UNITED STATES PATENT OFFICE

AUSTIN E. ELMORE, OF LOS ANGELES, CALIFORNIA

COMPRESSOR

Application filed April 30, 1929. Serial No. 359,213.

This invention relates to a compressor unit for supplying a fluid under pressure and involves details of construction contributing to efficiency, long life, compactness and silence of operation. The present invention appertains to a rotary compressor having reciprocable vanes and provided with a muffler means on the intake side and a discharge air chamber.

10 The objects of this invention are to provide a unit of the character described having any or all of the following features: a loose ring in the rotor to cause the vanes to follow the wall of the rotor chamber; novel 15 passing means for the vanes; a discharge chamber having lubricant separating means; an oil passage for delivery of separated lubricant to the rotor chamber; a regulating valve for controlling the actuated 20 fluid pressure and bypassing air or actuated fluid from the discharge chamber to the intake; a muffler intake chamber; and novel muffling means.

These objects together with other objects 25 and corresponding accomplishments are obtained by means of the embodiments of my invention illustrated in the accompanying drawings in which:—

Fig. 1 is an elevation of the complete unit, 30 Fig. 2 is a front elevation thereof; Fig. 3 is a vertical section as seen on the line 3—3 of Fig. 2; Fig. 4 is a section on the line 4—4 of Fig. 3; Figs. 5, 6 and 7 are sections as seen on the lines correspondingly numbered in Fig. 4; and Fig. 8 is a section as seen on the line 8—8 of Fig. 5.

Referring with more particularity to the drawings, the unit comprises a rotary pump A having an intake chamber B and a receiver or discharge chamber C. A pressure regulating valve is marked D and a rotary intake muffler E.

Referring more specifically to the rotary pump, it comprises a shell 10 provided with 45 peripheral cooling ribs and having a base 11 for supporting the unit upon any suitable bed. Closing the ends of the shell are heads 12 and 13. The heads are provided with extensions to receive ball bearings indicated generally by 14 and 15. These

bearings have a drive shaft 16 journaled therein, the drive shaft being mounted eccentric to the periphery of the shell. Fixed to the drive shaft is a cylindrical rotor 17 having recesses on opposite sides to receive 55 rings 18 and 19. The rings are loosely mounted and engage vanes 20 which are reciprocably mounted in the rotor so as to be movable radially in relation to the latter.

The rings are of such external diameter, that 60 they cause the vanes to follow the wall of the shell in their rotation. In order to provide an efficient leak tight packing between the vanes and the shell, packing strips 21 are mounted in grooves in the vanes and are 65 urged outwardly by compression springs 22.

The construction is such that upon rotation of the rotor, the vanes will be maintained in contact with the wall of the shell. The rotor is mounted so that its closest approach 70 to the shell is at the top of the latter. Extending across the shell and opening through the head is an intake 23 having ports 23a communicating with a rotor chamber. An outlet 24 extends through the 75 shell and through the head 13, communicating with the chamber through ports 24a. A groove 25 is provided in the flange of the shell extending from the bottom part thereof to a point adjacent the intake. 80

A passage 25a leads inwardly from the groove 25 and communicates with a port 25b opening to the intake. The port 25b is part of a cross passage, threaded at one end to receive the stem of a needle valve 26, there 85 being a seat for the needle valve at port 25b. The head of the needle valve is disposed so that the latter may be adjusted to regulate the flow of oil through port 25b.

Mounted over the head 13 is the receiver 90 chamber dome 27 provided with a boss 28 having a chamber registering with the intake 23. A port 29 serves for communication of the chamber in the boss with the compartment of the receiver chamber. A shoulder 95 is provided in the receiver chamber and a partition wall 30 is disposed therein dividing the chamber into an outlet compartment 31 and a discharge compartment 32. A port 33 for passage of the compressed fluid from the 100

- outlet compartment to the discharge compartment is provided in the partition wall and on the discharge compartment side of the wall is a baffle 34 ranging downwardly from the port 33. This baffle is to arrest oil or lubricant which may pass through the port. At the lowest side of the partition wall is an oil port 35 for oil to drain from the discharge compartment into the outlet compartment.
- 10 A passage 36 is provided in the receiver dome and communicates with a port in the head 13 which opens to the oil duct 25. Oil which collects in the receiver chamber may drain gravitatively into the oil duct and be moved upwardly to the intake where it is mixed with the incoming air and delivered to the rotor chamber. The receiver dome has a discharge outlet 37, which opens to the discharge compartment through an entry passage 38 formed on the wall of the dome. The entry passage assists in preventing oil from passing from the receiver chamber, a tortuous passage for the air being formed by the baffle and the entry passage.
- 15 In the bore of the boss is a cage 39 for a valve of the poppet type 40, this valve having a stem 41 threaded at its outer end. The sleeve is provided with a cylindrical enlarged portion 42 upon which is mounted a collar 43. A compression spring for the valve is marked 44 and abuts a spring seat 45 threaded upon the end of the stem so that by turning the spring seat, the compression of the spring 44 may be adjusted. The spring seat is in 20 the form of a nut having flat sides and is slidably received in a wrench member 46 fixed to a rotatable head 47. The rotatable head is conveniently secured to the collar 43 by means of a split expansion ring mounted 25 in corresponding recesses in the head and the collar. The valve seats so that it opens from the discharge side of the compressor into the intake, and may be adjusted so that the discharge pressure is sufficient, the valve 40 will 30 unseat and from this the compressed fluid can be bypassed into the intake. The pressure at which this occurs may be adjusted by turning the head 47.
- 35 Mounted over the head 12 is an intake dome shell 49 having an extension 50 registering with the intake 23. A port 51 serves for communication between the compartment of the intake dome and the chamber in extension 40 placing the intake dome in communication with the intake of the compressor. Disposed about and fixed on the drive shaft 16 is a rotary muffler bushing 52 having ports and passages 53 which serve for communication of the intake compartment with the atmosphere or source of supply of fluid to be compressed. Air is drawn through the rotary muffler into the intake chamber and thence to the intake, and due to the radial direction of the passages, the muffler acts as a centrifugal impeller to aid in the introduction of air.

In the operation of the unit, rotation of the rotor causes air to be drawn from the intake chamber to the intake and thence into the rotor chamber from whence it is moved to the outlet ports 24a and compressed in its 70 passage. Under normal operating conditions, the air passes from the outlet into the receiver chamber where the oil is separated and the cleaned compressed air then passes through the entry passage 38 and out the discharge 37, and may be delivered by a suitable pipe or hose to the point desired. Lubricant is initially supplied through the rotor chamber. Some of this lubricant will be carried out through the outlet into the receiver 75 chamber and will drain from the latter through the oil duct 25 back to the intake of the compressor. If for any reason an air pressure in the receiver chamber should increase beyond the amount desired and for 80 which the poppet valve is set, then the poppet valve will open and air is delivered back to the intake of the compressor. The operation is silent, a high degree of pressure may be obtained, and this is effectively regulated by the 85 poppet valve. Clean air is delivered and due to the receiver chamber without pulsation. Furthermore, silence is obtained by reason of the intake muffler and the receiver chamber.

90 What I claim is:—

- 95 1. A fluid compressor unit including a rotary pump comprising a rotor chamber having a cylindrical shell and heads thereon, a rotor eccentrically mounted with relation to said chamber, reciprocable vanes mounted in said rotor, a ring loosely mounted in said rotor and bearing against the inner ends of said vanes to cause the latter to follow the wall of said chamber, an intake in said chamber for fluid, an outlet in said chamber for fluid; a receiver chamber disposed on the side of said rotor chamber comprising an air dome, a partition wall dividing said chamber into an outlet compartment and a discharge compartment and having a fluid port at one 100 side for passage of fluid therethrough, said outlet compartment directly communicating with said outlet, said partition wall having an oil port for gravitational flow of oil from said discharge compartment to said outlet 105 compartment, a baffle disposed in said discharge compartment over said fluid port and ranging toward said oil port, a discharge outlet communicating with said discharge compartment, an oil duct formed between the 110 head on the receiver chamber side of said rotor chamber and said shell leading from the bottom of said outlet chamber to said intake.
- 115 2. A fluid compressor unit including a rotary pump comprising a rotor chamber having a cylindrical shell and head mounted thereon, a rotor eccentrically mounted with relation to said chamber, reciprocable vanes mounted in said rotor, a ring loosely mounted in said rotor and bearing against the inner 120
- 125

ends of said vanes to cause the latter to follow the wall of said chamber, an intake in said chamber for fluid, an outlet in said chamber for fluid; a receiver chamber disposed on the 5 side of said rotor chamber comprising an air dome, a partition wall dividing said chamber into an outlet compartment and a discharge compartment and having a fluid port at one side for the passage of fluid there- 10 through, said outlet compartment directly communicating with said outlet, said partition wall having an oil port for gravitational flow of oil from said discharge compartment to said outlet compartment, a baffle disposed 15 in said discharge compartment over said fluid port and ranging toward said oil port, a discharge outlet communicating with said discharge compartment, an oil duct formed between the head on the receiver chamber side 20 of said rotor chamber and said shell leading from the bottom of said outlet chamber to said intake, and a valve for regulating the flow of oil through said duct.

3. A fluid compressor unit including a rotary pump comprising a rotor chamber, a rotor eccentrically mounted with relation to said chamber, reciprocable vanes mounted in said rotor, a ring loosely mounted in said rotor and bearing against the inner ends of 25 said vanes to cause the latter to follow the wall of said chamber; an intake chamber on said rotor chamber comprising a dome disposed over a head on said rotor chamber, a drive shaft for said rotor extending through 30 said intake chamber, a rotary muffler bushing in the wall of said intake chamber and through which said drive shaft passes, said muffler bushing having a multiplicity of ports placing the compartment of said intake 35 chamber in communication with the source of supply for the fluid to be compressed, said intake chamber communicating with the intake of said rotor.

4. A fluid compressor unit including a rotary pump comprising a rotor chamber, a rotor eccentrically mounted with relation to said chamber, reciprocable vanes mounted in said rotor, a ring loosely mounted in said rotor and bearing against the inner ends of 45 said vanes to cause the latter to follow the wall of said chamber, an intake for said chamber, an outlet for said chamber; a receiver chamber disposed on the side of said rotor chamber comprising an air dome, said receiver chamber directly communicating with said outlet, a discharge outlet communicating with said receiver chamber; an intake chamber on said rotor chamber comprising a dome disposed over the other head of said rotor 50 chamber, a drive shaft for said rotor extending through said intake chamber, a muffler bushing in the wall of said intake chamber and through which said drive shaft passes, said muffler having a multiplicity of ports placing the compartment of said intake chamber into communication with the source of supply for the fluid to be compressed, said intake chamber and intake being in communication, said intake extending to said receiver chamber, a pressure poppet regulating valve controlling communication of said receiver chamber with said intake, a spring to urge 55 said valve to its seat and means to adjust the spring effort.

ment of said intake chamber into communication with the source of supply for the fluid to be compressed, said intake communicating with the compartment of said intake chamber.

5. A fluid compressor unit including a rotary pump comprising a rotor chamber, a rotor eccentrically mounted with relation to said chamber, reciprocable vanes mounted in said rotor, a ring loosely mounted in said rotor and bearing against the inner ends of said vanes to cause the latter to follow the wall of said chamber, an intake for said chamber, an outlet for said chamber; a receiver chamber disposed on the side of said rotor chamber comprising an air dome, said receiver chamber directly communicating with said outlet, a discharge outlet communicating with said receiver chamber; an intake chamber on said rotor chamber comprising a dome disposed over the other head of said rotor chamber, a drive shaft for said rotor extending through said intake chamber, a muffler bushing in the wall of said intake chamber through which said drive shaft passes, said muffler bushing having a multiplicity of ports placing the compartment of said intake in communication with the source of supply for fluid to be compressed, said intake extending to said receiver chamber, a pressure regulating valve controlling the communication of said receiver chamber with said intake.

6. A fluid compressor unit including a rotary pump comprising a rotor chamber, a rotor eccentrically mounted with relation to said chamber, reciprocable vanes mounted in said rotor, a ring loosely mounted in said rotor and bearing against the inner ends of said vanes to cause the latter to follow the wall of said chamber, and intake for said chamber, an outlet for said chamber; a receiver chamber disposed on the side of said rotor chamber comprising an air dome, said receiver chamber directly communicating with said outlet, a discharge outlet communicating with said receiver chamber; an intake chamber on said rotor chamber comprising a dome disposed over the other head of said rotor chamber, a drive shaft for said rotor extending through said intake chamber, a muffler bushing in the wall of said intake chamber and through which said drive shaft passes, said muffler having a multiplicity of ports placing the compartment of said intake chamber into communication with the source of supply for the fluid to be compressed, said intake chamber and intake being in communication, said intake extending to said receiver chamber, a pressure poppet regulating valve controlling communication of said receiver chamber with said intake, a spring to urge said valve to its seat and means to adjust the spring effort.

7. A fluid compressor unit including a rotary pump comprising a rotor chamber, a rotor eccentrically mounted with relation to said chamber, reciprocable vanes mounted in said rotor, a ring loosely mounted in said rotor and bearing against the inner ends of said vanes to cause the latter to follow the wall of said chamber, an intake for said chamber, an outlet for said chamber; a receiver chamber disposed on the side of said rotor chamber comprising an air dome, said receiver chamber directly communicating with said outlet, a discharge outlet communicating with said receiver chamber, an intake chamber on said rotor chamber comprising a dome disposed over the other head of said rotor chamber, a drive shaft for said rotor extending through said intake chamber, a muffler bushing in the wall of said intake chamber and through which said drive shaft passes, said muffler bushing having a multiplicity of ports placing the compartment of said intake chamber in communication with the source of supply for the fluid to be compressed, the compartment of said intake chamber communicating with said intake, said intake extending to said receiver chamber, a pressure poppet regulating valve controlling communication of said receiver chamber with said intake, said valve having a stem, a spring to urge said valve to its seat, a spring seat member threaded on said stem for adjusting the spring effort, and means on the outside of said unit to adjust said spring.

In witness that I claim the foregoing I have hereunto subscribed my name this 24th day of April, 1929.

AUSTIN E. ELMORE.
